UNITED STATES PATENT OFFICE.

WILLIAM H. PRITCHETT, OF THE UNITED STATES MARINE CORPS.

PORTABLE FIELD SHOWER-BATH.

1,241,764.

Specification of Letters Patent.

Patented Oct. 2, 1917.

Application filed July 17, 1917. Serial No. 181,131.

To all whom it may concern:

Be it known that I, WILLIAM H. PRITCHETT, of the United States Marine Corps, a citizen of the United States, stationed at 5 Sanchez, in the Dominican Republic, have invented certain new and useful Improvements in Portable Field Shower-Baths; and I do hereby declare the following to be a full, clear, and exact description of the invention, such as will enable others skilled in the art to which it appertains to make and 10 use the same.

My present invention relates to improvements in portable shower baths, and is intended more especially to provide a portable shower bath which may be conveniently carried by troops in the field, or by landing parties from naval vessels, or for use by hunters, travelers, or others where bathing facilities 20 are lacking.

The invention is especially adapted for use for troops in the field in warm weather, as in campaigning in tropical countries, where bathing facilities are lacking.

According to my invention I provide a reservoir, preferably in collapsible form, such as a canvas bag, with a suitable supporting means; and in the bottom of this bag I place a shower attachment, which may be readily 25 turned on or off by the bather, and when not in use the bag may be folded up and carried along with the other baggage of the troops. Under certain conditions instead of a canvas bag a suitable bucket or can of any kind 30 might be used.

My invention will be more fully understood after reference to the accompanying drawings, in which—

Figure 1 shows the entire apparatus suspended from a limb of a tree, parts being broken away;

Fig. 2 shows a central vertical section through the bottom of the apparatus shown in Fig. 1;

Fig. 3 shows a section along the line 3—3 of Fig. 2, and looking down; and

Figs. 4 and 5 are details showing in side elevation, the stock and stem, respectively, of the shower attachment.

1 represents a suitable receptacle adapted 50 to contain water, preferably a water-proof canvas bag, which may be folded up and stored when not in use, and transported from place to place. This receptacle may be suspended in any convenient way as by the loop 55 or bail 2, which may be hung over any suitable support, such as the limb of a tree 3, shown in Fig. 1.

In the bottom of the receptacle 1, I mount a hollow stock 4, having an internally 60 tapered bore 5, with one or more openings 6. In the figures I have shown two of such openings; but one or more may be used. This stock is provided with an annular flange 7, and with a screw-threaded base 8. 65 Over this screw-threaded base the washer 9 is screwed, clamping the bottom of the receptacle between it and the annular flange 7 of the stock; and below this washer 9 I provide a lock nut 10, which prevents the 70 washer from coming loose.

Rotatably mounted in the chamber 5 in the stock is the tapered stem 11, which fits snugly within said chamber, and is provided with one or more perforations 12, two of 75 which are shown in Figs. 3 and 5, and which perforations are adapted to register with perforations 6 in the stock when the stem is turned through the required angle. The upper end of the stem 13 is preferably made 80 angular in shape for convenience in assembling the parts, and the lower end of the stem is screw-threaded as at 14 to engage the screw threads 15 on the neck 16 of the shower-head 17. The shower-head is provided with 85 a scattering plate 18, provided with suitable perforations 19, so that the water may be separated into a series of fine sprays.

To use the invention, suspend the receptacle 1 to any convenient overhead support, 90 and at the desired height for the bather to pass beneath, preferably to stand upright beneath the same. The receptacle being filled with water, and the parts being in the position shown in Figs. 1 and 2, the bather 95 goes beneath the shower-head 17, and by turning the same with his hands is enabled to turn the stem 11 so that the passages 12

will wholly or partly register with the passages 6 in the stock. This will effect the flow of water from the receptacle down the stem into the shower-head whence it will 5 spray on the bather.

When it is desired to discontinue the act of bathing, the bather can simply twist the shower-head 17 back to the initial position, closing the ports 12, and cutting off the flow 10 of water.

When it is desired to pack away the device for transporting or storage, the shower-head may be either left in place, or preferably the shower-head may be removed from 15 the stem, which can be accomplished by holding on to the head 13 with a wrench, while unscrewing the shower-head from the said stem, and these two parts may be rolled up in the bag, or stored in the bottom of the 20 receptacle, as preferred.

The stock, with its fastening nut and washer, would ordinarily remain permanently attached to the bottom of the receptacle, and if it be desired to use the receptacle for other purposes than bathing, it 25 will be sufficient merely to put a suitable cork or stopper into the tapered chamber in the stock, when the receptacle can be used as an ordinary bucket for transporting 30 water, food for man or beast, or other articles. In such case, of course, the stem and shower-head would have been previously removed before the stopper was inserted in the stock.

While the apparatus would be more convenient for transport and storage if the receptacle were made of a waterproof canvas bag, with a shower-head attachment fastened in the bottom thereof, any suitable container 40 for liquid may be used, such as a galvanized iron bucket, or a wooden barrel, or any other receptacle that might be available. Such receptacle might be located at the desired altitude and filled with water, or it may be 45 lowered and filled, and then hoisted to the desired position.

For use with troops, smaller receptacles with corresponding shower attachments may be provided for individual officers, and 50 larger receptacles for squads or larger bodies of men.

The device would be especially adapted also for bathing in arid countries where water is not found in pools; but has to be 55 derived from wells, or springs, or the like.

It will be seen that I provide a cheap and simple portable shower bath apparatus, which is adapted to stand the rough usage incident to field service, and which may be 60 readily put in place, if desired, and the parts of which may be readily assembled, or disassembled, as desired, and in which there is no necessity for unnecessary waste of water.

This apparatus is obviously especially

adapted for use in tropical countries where 65 water can be had, but where bathing facilities happen to be bad.

It will be obvious that various modifications might be made in the herein described apparatus, and in the construction, combination and arrangement of parts, which could be used without departing from the spirit 70 of my invention.

Having thus described my invention, what I claim and desire to secure by Letters Pat- 75 ent of the United States is:

1. A portable field shower bath comprising a receptacle, a chambered stock projecting through the base of said receptacle and secured thereto, the said stock being provided with one or more lateral ports, a stem rotatably mounted in said stock and having one or more ports adapted to register with the ports in the stock, the said stem having its base projecting beyond the bottom of 85 said stock, and a shower-head attached to said stem below said stock and adapted to rotate said stem when turning pressure is applied thereto, substantially as described.

2. A portable field shower bath comprising 90 a receptacle, a stock having a tapered chamber therein projecting through the base of said receptacle and secured thereto, the said stock being provided with one or more lateral ports, a hollow stem in the 95 form of a frustum of a cone rotatably mounted in said stock and having one or more ports adapted to register with the ports in the stock, the said stem having its base screw-threaded and projecting beyond the 100 bottom of said stock, and a shower-head screwed tight on said stem below said stock and adapted to rotate said stem when turning pressure is applied thereto, substantially 105 as described.

3. A portable field shower bath comprising 110 a collapsible receptacle, a stock having a tapered chamber therein projecting through the base of said receptacle and secured thereto, the said stock being provided with one or more lateral ports, a hollow stem in the form of a frustum of a cone 115 rotatably mounted in said stock and having one or more ports adapted to register with the ports in the stock, the said stem having its base screw-threaded and projecting beyond the bottom of said stock, and a shower-head detachably secured to said stem below said stock and adapted to rotate said stem when turning pressure is applied thereto, 120 substantially as described.

4. A portable field shower bath comprising 125 a collapsible receptacle, a stock having a tapered chamber therein projecting through the base of said receptacle and secured thereto, the said stock being provided with one or more lateral ports, a hollow stem in the form of a frustum of a cone

rotatably mounted in said stock and having one or more ports adapted to register with the ports in the stock, the said stem having its base screw-threaded and projecting beyond the bottom of said stock, and a shower-head screwed tight on said stem below said stock and adapted to rotate said stem when

turning pressure is applied thereto, the said stem and shower-head being detachably connected to said stock, substantially as described. 10

In testimony whereof I affix my signature.

WILLIAM H. PRITCHETT.
